MILL

Robert S. Butler, Santa Monica, Calif., assignor
to Sullivan Machinery Company, a corporation
of Massachusetts

Application December 31, 1934, Serial No. 759,903
Renewed June 12, 1939

16 Claims. (Cl. 83—9)

This invention relates to size reducing mills, and particularly to size-reducing mills for reducing material such as rock, ore, retort residues, coal, etc. from pieces of substantial size to a degree of fineness suitable for pulverizing.

An object of my invention is to provide an improved size-reducing mill. Another object of my invention is to provide an improved crusher of very simple construction and great efficiency. A further object of my invention is to provide an improved size-reducing mill which may embody a single stage of size reducing apparatus or a plurality of stages, as desired. Yet another object of my invention is to provide an improved size-reducing mill adapted for continuous feed and having, in a machine of small size and relatively light weight, an output equal to that of much larger size-reducing mills of familiar types. Still another object is to provide an improved size-reducing mill in which the kinetic energy of relatively moving parts and frequent reversals of direction are availed of to effect a very rapid and positive crushing action. Other objects and advantages of my invention will hereinafter more fully appear.

In the accompanying drawings, in which several illustrative embodiments of my present invention are shown,—

Fig. 1 is a view, primarily in central vertical section, but with some parts shown in full, through one illustrative form of the size-reducing mill.

Fig. 2 is a vertical transverse section on a plane corresponding to the line 2—2 of Fig. 1.

Fig. 3 is a view similar to Fig. 1, showing a modified form of construction in which plural staging is incorporated.

Fig. 4 is a transverse vertical section on a plane corresponding to the line 4—4 of Fig. 3.

Fig. 5 is a fragmentary view, partially in central longitudinal section and partially in elevation, through a modified form of single stage size-reducing mill.

Fig. 6 is an end view of the construction shown in Fig. 5.

Fig. 7 is a view similar to Fig. 5, showing a further modification.

Fig. 8 is an end view of the structure shown in Fig. 7.

Fig. 9 is a view, partially in side elevation and partially in vertical section, showing a further modified form of mill.

Referring first to the species of the embodiment of the invention shown in Figs. 1 and 2, it will be observed that a suitable rugged frame 1

supports, in a suitable bearing 2, a crank shaft 3 having a combined driving pulley and flywheel 4. The crank shaft has a crank pin 5 connected by a suitable connecting rod 6 to a wrist pin 7 suitably supported in projecting brackets 8 which are secured to the front head of a reciprocable size-reducing-chamber-providing element or unit 9. This unit herein comprises a front head 10, a rear head 11, a top 12 having a flared charge-receiving portion 13, side plates 14, holding rods 10 15, and spacing sleeves 16 which also serve as guides for the size-reducing medium, and some of which serve to preclude discharge of material not reduced in size to the desired degree. It will be observed that the heads 10 and 11 are held in 15 spaced relation to each other by the spacing sleeves 16; that the side plates 14 are bolted at 17 to the end plates; that the top plate is suitably attached in any desired manner, as by welding, to the end plates; that the bottom of 20 the casing 9 is open, and that the top supports the material-receiving chute 13 and receives the material to be crushed and broken through opening 18 surrounded by the bottom portion of the supply chute 13 and divided by a deflector 19. 25 The size-reducing or crushing medium may advantageously consist of one or more balls 20 of relatively large size and substantial mass, and with the device illustrated the size-reducing action is derived very largely from the kinetic energy of the ball and of the casing element. It will be noted that the sleeves 16 are so space-related to each other and to the side plates that there is possible a slight movement of the ball 20 off the lower sleeves in passing over material of large 30 size, etc., that the ball may at times engage the side plates, and that the side plates at times limit lateral movement of the ball. The member 9 is provided adjacent its bottom with angle portions 21, and between the depending lugs of these angle 40 portions and the bottoms of the sides of the casing there are journaled rollers 22 by means of pivot pins 23, and these rollers support the casing 9 for reciprocation upon guides 24 at opposite sides of a discharge opening 25 formed in the 45 base 1. Suitable guideways 26 bolted at 27 to the base frame guide the casing 9 for reciprocation.

It is very important to select the throw of the crank 5 and to determine the free travel of the size-reducing or crushing media so that the most effective size-reducing action will be obtained. Were it not for the fact that the rock masses to be broken occupy a substantial and variable portion of the free space between the free size-reducing medium (herein the ball) and the ends of 55

the chamber, the matter of obtaining maximum impact would be quite simple, as it would simply be necessary to select a chamber dimension of such length that the ball charge, whose velocity 5 may be considered to be substantially constant (aside from the retardation due to friction and load, this is relatively true), would coact, in effecting size reduction, with the oppositely moving chamber head substantially as the latter attained 10 to its maximum velocity. The crank throw and ball size obviously, therefore, both affect chamber length. The hardness and friability of the material affect ball size and weight, the ratio of size to weight increasing with the, so to speak, 15 degree of easy crushability of the material, so that for material easy to crush a relatively large hollow ball can be used to effect rapid size-reduction. The force of the blow is a function of velocity and mass, and therefore the stroke of the 20 casing can be determined from the ascertained necessary force of blow to crush the material. Now, having selected a ball size (and weight, of course) and determined the crank throw, and disregarding, for simplicity, the effect of the 25 angularity of the connecting rod, it may be said that the internal length of the size-reducing chamber should be made approximately equal to: $b + 1\frac{1}{2}m + 1\frac{1}{2}s$ —when b =ball diameter (assuming only one ball used), m =material charge 30 dimension longitudinally of the chamber at the instant crushing commences at one end of the chamber, and s =the stroke of the chamber. The chamber dimension should be increased if the length of the free medium (ball) be increased. 35 The dimensions of the supply chute 13 may be varied; and by providing a definite feed rate and using a partition, as at 19, to insure delivery at the proper end of the chamber, all possibility of choking may be avoided.

40 The structure so far described will operate as follows: The combined flywheel and driving pulley 4 being rotated by a suitable driving motor, the crank pin 5, through the connecting rod 6 and pin 7, will cause reciprocation of the size-reducing chamber 8. Suitably graded material 45 will be supplied at a desired rate through the chute 13, and will pass alternately into one end of the chamber or the other, into the path of travel of the relatively moving size-reducing elements. Then, the size reducing medium (ball), traveling at high velocity in one direction, and an oppositely moving chamber head will coact to crush the material between them. To prevent material inadequately reduced in size from passing 50 through the chamber without engagement by the size-reducing medium, there could be provided, if desired, one or more additional guide sleeves, suitably supported between the outermost pair below the ball so as to make a discharge grid and permit the escape only of particles reduced to a predetermined maximum size. It will be understood that there will be two crushing actions during each rotation of the crank shaft, and assuming rotation of the latter to be counter-clockwise in Fig. 1, it will be understood that from 55 the crank position shown through the next half-revolution (disregarding the angularity effect) the ball will move away from the decelerating chamber, the chamber will reverse its movement 60 while the ball travels freely, and then when the chamber has attained substantially top speed in the opposite direction, crushing will take place.

In the construction shown in Figs. 3 and 4, it 70 will be observed that a plural stage size-reducing chamber element has been shown. Here the end

plates 10' and 11' are made of such size that it is possible to provide a second size-reducing mechanism beneath the primary size-reducing mechanism which is arranged directly below the supply chute 13. To accommodate this secondary crushing stage, it will be noted that a third series of spacing sleeves 16 is arranged in parallelism with the upper two series, and a second crushing medium consisting of another ball 20' is arranged to travel back and forth upon the lowermost series of guide sleeves 16. This lower ball may be of different size from the upper one, and need not be of the same mass as the upper ball, as the rock or other material which attains to its action is of reduced size, and therefore does not require a blow of the same intensity to crush it as is the case with larger pieces. Like balls (as illustrated) may, however, be used in both chambers if maximum reduction is desired. In this form of the invention, the second or middle series of guides, which guide the upper ball element 20, are spaced a greater distance apart than the bottom series, but less far apart than the top series, and intermediate guides need not be provided in the second series to the extent to which this may be desirable in the first form of the invention. The mode of operation of this form of the invention and the further structure thereof do not need particular description, as, except for the differences mentioned and the plural staging, the construction is much the same as in Figs. 1 and 2. Here both the primary and secondary crushing or breaking media (balls) are simultaneously reciprocated, and more or less simultaneously act upon the material in different stages of size-reducing mechanism of the latter. With a compound size-reducing mechanism, such as is illustrated in this embodiment of the invention, due to the fact that even relatively large fragments of rock are broken not only into a few relatively substantial sized pieces, but into many smaller fragments, the average size of the rock fragments and particles leaving the second stage will be quite small.

In Figs. 5 and 6, another mode of mounting the size-reducing chamber is illustrated. In this construction, a size-reducing chamber 39, substantially the same as that shown in Figs. 1 and 2 except for the absence of the supporting means including the angle members 21 supporting rollers 22 and pins 23, is provided. Here the chamber is supported by parallel link pairs 40, 40 and 41, 41, these being pivotally connected at their lower ends to the now-heavier side frame elements 42 at the top of the size-reducing chamber and also pivotally supported at their opposite (upper) ends on pins 44 supported in brackets 45 carried by a frame portion 46 suitably supported in any appropriate manner, as by side plates or supporting members 48 from the base 1'. In this case, it will be obvious that the size-reducing chamber 39 will not have a rectilinear reciprocatory motion, but will have an oscillatory movement, though at all times remaining in mutually parallel positions. This construction will not provide a markedly different crushing action, but will avoid the necessity for roller bearings which may, under some circumstances and unless adequately protected, give trouble in the presence of abrasive material.

Referring to Figs. 7 and 8, it will be noted that in this form of the invention I have provided means for supporting the chamber including means for storing energy each time the chamber moves out of mid-position. Such means may ob-

viously include combined support and energy-storing means, or separate means for each function. While not employing the parallel link pairs 40 and 41, I support the size-reducing chamber in a manner very similar to that shown in Figs. 5 and 6, through the use of leaf springs 50, 51 arranged in pairs at opposite ends of the size-reducing chamber and pivotally connected to the latter at 52 while rigidly mounted at their upper ends at 53 between angle plates or other suitable holding means fixed to the frame member 46. This form of the invention provides an advantage in that the flywheel weight may be reduced, because the springs store energy during the movements out of central position of the size-reducing chamber and return that energy as the size-reducing chamber moves back into central position. The mode of operation is not, in so far as size-reducing per se is concerned, markedly different from that 20 of the other forms described.

In Fig. 9, to provide completely uniform travel and operation on the opposite passes of the size-reducing chamber, I mount a chamber 60, of like form to that of Fig. 1 and with a like free size-reducing member (not shown), by means of similar guides and rollers, but reciprocate the chamber by means of a Scotch yoke arrangement, employing a rod 61, yoke 62 and crank pin 63 to provide identical opposite movements of the 30 casing or chamber. An important feature in each form of the invention described, although not one which is essential to all the aspects of my invention, is the relative height of the balls and chambers, whereby the material is caused to be struck very completely upon every stroke.

In each form of the invention, it will be obvious that I have provided an improved size-reducing arrangement in which extreme simplicity is accomplished, in which the kinetic energy of the 40 moving size-reducing chamber member and free size-reducing medium may be availed of most advantageously in reducing the size of the material, in which a single relatively large ball and its power-moved chamber may be caused to accomplish a very large amount of material-reduction, as compared with the larger and more cumbersome mills of the prior art, and in which there is a direct and inevitable size-reducing or crushing action between oppositely moving parts 45 twice in each complete rotation of the driving shaft.

While I have in this application specifically described five forms which the invention may assume in practice, it will be understood that these 55 forms are shown for purposes of illustration and that the invention may be further modified and embodied in various other forms without departing from its spirit or the scope of the appended claims.

60 What I claim as new and desire to secure by Letters Patent is:

1. In a mill, a chamber guided for movement in opposite directions and having guides therein extending in its direction of movement and which 65 remain parallel to the same fixed straight line throughout chamber movements, a ball in said chamber confined by said guides to movement in a zone of uniform height not substantially exceeding ball diameter either laterally or upwardly 70 and downwardly, means for introducing material into said chamber through the top thereof, means for discharging material from said chamber through the bottom thereof, and means for moving said chamber lengthwise back and forth 75 through the same set of positions in each direc-

tion, said chamber, chamber moving means, and ball of such relative dimensions that said ball has a free lengthwise travel greater than chamber movement when said chamber is empty and, during size-reduction, coacts once in each full cycle 5 of movement of the size-reducing chamber with each head of the chamber to crush material by the kinetic energy of the relatively moving parts.

2. In a mill, a frame, an elongated size-reducing chamber having an open bottom and supported on said frame for movements during which the same remains at all times parallel to a given fixed straight line, a free size-reducing medium in said chamber, guiding means for said size-reducing medium extending lengthwise of said 10 chamber and spaced relative to each other and to the chamber walls to provide guiding support from beneath and path restriction above for said size-reducing medium whereby the paths of motion of the latter and the motion of said 15 chamber are closely similar, and means for reciprocating said chamber lengthwise thereof with an amplitude less than the difference between the interior length thereof and the dimension, lengthwise of said chamber, of said size-reducing medium. 20

3. In a mill, a frame, a member providing an elongated chamber and supported for opposite movements longitudinally through a series of 30 positions in which it at all times remains parallel to a given fixed straight line extending in the direction of elongation of the chamber, a size-reducing medium in said chamber, guide bars supporting said size-reducing medium and serving as a discharge grating, and other guide bars 35 constraining said size-reducing medium to movement in a zone of substantially unit size-reducing medium height.

4. In a mill, a reciprocable elongated size-reducing chamber, a free size-reducing medium 40 therein, and feeding means for said chamber providing for delivery thereto of material through a pair of openings spaced from each other longitudinally of said chamber and beneath which in alternation the size-reducing medium lies in the 45 size-reducing positions of the latter.

5. In a mill, a frame, an elongated size-reducing chamber guided on said frame for rectilinear movement, a single relatively large free ball in said chamber, said ball of such dimension and 50 said chamber so formed that the center of said ball is constrained to remain in or closely adjacent to the central longitudinal vertical plane of said chamber during relative movement between said ball and chamber and that escape of 55 material laterally out of the path traversed by said ball is precluded, and means for positively reciprocating said chamber to effect coaction of said ball with the chamber ends in alternation.

6. In a mill, a frame, an elongated size-reducing chamber supported on said frame for movements during which the same remains at all times parallel to a given fixed straight line, a free size-reducing medium in said chamber, longitudinally extending guiding means for the latter providing guide rails for guiding the size-reducing medium smoothly longitudinally of the chamber and operative to maintain said size-reducing medium substantially central both laterally and vertically of said chamber during its 70 movements therein and providing also means for precluding material in excess of a given size from leaving said chamber, and means for reciprocating said chamber. 75

7. In a mill, a frame, a box providing an elong-

- gated size-reducing chamber having a feed opening in its top and its bottom open from end to end and from side to side, guide bars extending in spaced relation to the chamber walls from end to end of the latter and other guide bars more closely spaced extending in spaced relation to said chamber from end to end of the latter below said first mentioned bars, a free size-reducing medium supported on said lower bars and confined against substantial lifting therefrom by said upper bars, and means for rapidly moving said chamber alternately in opposite directions. 5 10 15 20 25 30 35 40 45 50 55 travel and the dimension longitudinally of said chamber of said crusher member.

5. 15. In a mill, a chamber guided for movement in opposite directions and having longitudinally extending walls for confining material while the same is being reduced in size and further having guides therein which extend in the direction of chamber movement and which remain parallel to the same fixed straight line throughout chamber movements, a ball charge in said chamber guided by said guides for movement, when said chamber is empty of material, out of contact with but in close contiguity to the longitudinally extending walls of said chamber and confined by said guides to movement in a stratum of approximately unit ball thickness, and means for imparting to said chamber alternate movements in opposite directions, said chamber and said ball charge of such relative dimensions longitudinally 10 of said chamber that said ball charge has a path of free movement in said chamber at least equal in length to chamber movement and that a ball-charge and chamber-end coaction, to crush rock by the kinetic energy of the parts, occurs twice 15 during each full cycle of movement of the crush- 20 25

ing chamber, and said ball charge, guides and longitudinally extending walls of such relative dimensions and so arranged that said walls act to hold material within the path of the ball charge during size-reduction.

5. 16. In a mill, a reciprocable elongated crushing chamber, means for reciprocating the same longitudinally, a free crushing medium enclosed within said chamber, said chamber and crushing medium of such relative dimensions and said chamber reciprocated with such speed that said crushing medium coacts alternately with the opposite chamber ends, and a feed device for said chamber providing for the delivery of feed thereto during chamber movement, in a direction transverse to the path of crushing-medium movement and between the ends of such path and including feed openings respectively positioned to admit material to the opposite ends of the chamber and through each of which material is admissible when the crushing medium is at its maximum distance from the chamber end for which such opening is provided.

ROBERT S. BUTLER. 25

CERTIFICATE OF CORRECTION.

Patent No. 2,168,085.

August 1, 1939.

ROBERT S. BUTLER.

It is hereby certified that error appears in the printed specification of the above numbered patent requiring correction as follows: Page 2, second column, line 5-6, for the word "crushing" read --size-reducing--; line 35-36, for "size-reducing mechanism" read --size-reduction--; line 66, for the word "crushing" read --size-reducing--; and that the said Letters Patent should be read with this correction therein that the same may conform to the record of the case in the Patent Office.

Signed and sealed this 25th day of June, A. D. 1940.

Henry Van Arsdale,
Acting Commissioner of Patents.
